UNITED STATES PATENT OFFICE

MARK L. BLAIR, OF FLINT, MICHIGAN, ASSIGNOR TO A C SPARK PLUG COMPANY,
OF FLINT, MICHIGAN, A CORPORATION OF MICHIGAN

BY-PASS FOR AIR CLEANERS

Application filed September 26, 1927. Serial No. 222,137.

This invention relates to improvements in air cleaners and, though of general application, is particularly applicable to air cleaners used to clean the air to be supplied to the carburetors of internal combustion engines.

When an air cleaner is used to clean the air to be supplied to the carburetor of an internal combustion engine, it is usually positioned on the end of a conduit leading to the air intake of the carburetor, the air being drawn through the cleaner and into the carburetor by the suction produced in the cylinder or cylinders of the engine on the induction stroke. The air cleaner inherently offers considerable resistance to the current of air which is passing through it and being cleaned. When the engine is running at normal speeds sufficient air for the needs of the engine can be drawn into the carburetor through the air cleaner. But when the engine is running at high speeds, the suction is increased and the amount of air required is greater than can ordinarily be drawn in through the cleaner due to the resistance offered to the air current by the dirt removing medium or dirt separating means therein. It is an object of the invention to provide means whereby an air supply sufficient for the needs of the engine is assured at all times.

It is another object of the invention to provide an air cleaner having an auxiliary air intake opening through which air may be admitted to the interior of the cleaner and pass out of the cleaner through the normal discharge opening without encountering the resistance set up by the dirt separating means.

It is another object of the invention to provide an air cleaner having a main air intake opening, an air discharge opening and an auxiliary air intake opening.

It is another object of the invention to provide an air cleaner having a main air intake opening, an air discharge opening, and an auxiliary valve controlled air intake opening which is adapted to admit air to the cleaner when the pressure within the cleaner reaches a predetermined point.

It is another object of the invention to pro-

vide an air cleaner having a valve controlled air intake opening.

Other objects of the invention will appear in the course of the following description of the embodiments of my invention which are shown in the accompanying drawings in which:

Figure 1 is a side elevation, with parts in section and broken away, of an air cleaner in which is embodied my invention.

Figure 2 is an end elevation of the air cleaner shown in Figure 1 with the bracket and its securing nut removed.

Figure 3 is a view, similar to Figure 1, of another type of air cleaner in which my invention is embodied.

Figure 4 is a view, similar to Figure 2, of the air cleaner shown in Figure 3.

Figure 5 is a fragmentary sectional view showing a modified form of control means for the auxiliary air intake openings.

Referring particularly to the embodiment of my invention shown in Figures 1 and 2, the reference character 10 indicates a cylindrical shell which forms the body portion of the air cleaner. A plate 11 is secured to one end of the shell 10 as by crimping its outer edge over a circumferential flange on that end of the shell as indicated at 12. The plate 11 is provided with a circular central opening through which projects into the interior of the cleaner the air discharge pipe 13 which is secured to the portion of the plate surrounding the opening. Between the central opening and its outer edge, the plate 11 is provided with a series of inwardly directed struck-out vanes 14 and adjacent air intake openings 15. Within the portion of the pipe inside the shell there is provided an air straightener blade 16.

Adjacent the end opposite the plate 11, the side wall of the shell is provided with a tangential dirt discharge opening 17. The end of the shell adjacent this opening is closed by a plate 18, which is secured to the side wall of the shell similarly to the plate 11. The plate 18 is provided with sectoral auxiliary air intake openings 19 arranged about a central annulus 20 and separated by spokes 21 integral with the annulus and the

outer portion of the plate. In order to avoid repetition, the description of the mounting of the supporting bracket and of the control means for the auxiliary air intake openings 5 19, which are identical with those shown in Figures 3 and 4, will be deferred until the general description of the air cleaner shown in Figures 3 and 4 has been completed.

In Figures 3 and 4, the reference character 10 40 indicates the body portion of the air cleaner, which is fustro-conical in shape and is provided at its smaller end with an integrally formed closure 41 having a central air discharge opening 42 therein. Extending around the greater part of the opening 42 and integral with the closure 41 is a collar 15 43. For a portion of its circumference the collar is separated from the closure 41, as indicated at 44. Intermediate the ends of this separated portion, the collar is split 20 and the free ends of the tongues thus formed bent outwardly to provide the lugs 45. The lugs 45 are perforated for the reception of a bolt which in conjunction with a nut is 25 adapted to draw the collar tightly around and secure it to the conduit which conducts the clean air away from the cleaner. In its side wall adjacent its smaller end, the body portion 40 is provided with a tangential dirt discharge opening 46.

The reference character 47 indicates a circular plate which is secured in the larger end of the body portion 40 of the cleaner by clamping its circumferential edge between the outwardly extending circumferential flange 48 and the crimped portion 49 thereof. The plate 47 is provided with sectoral auxiliary air intake openings 50 arranged about a central annulus 51 and separated by spokes 52 30 integral with the annulus and the outer portion of the plate. Between the outer edges of the openings 50 and its outer edge, the plate 47 is provided with a series of inwardly directed struck-out vanes 53 and adjacent air intake openings 54.

The following description applies to Figures 1-4 inclusive. The openings 19 (or 50) are normally closed by a valve disk 22 which has a circumferential flange 23 bearing against the inner side of the plate 18 (or 47). A rod 24 within the body portion of the cleaner passes through a central opening in the disk 22 and has a shoulder 25 bearing against the inner side of the annulus and a reduced end portion 26 passing through the central opening therein. The rod 24 is secured to the plate by a nut 27 which is threaded on the reduced portion of the rod and holds the shoulder firmly against the inner side of the annulus. A coiled spring 28 surrounds the rod 24, bearing at opposite ends against the disk 22 and the cup-shaped washer 29, which is held in place on the rod by the pin 30, and normally holds the disk 65 22 closely against the plate 18 (or 47).

The reference character 31 indicates a bracket which is used to support or mount the air cleaner in its operative position. The bracket is secured to the cleaner by a nut 32 threaded on the end of the reduced portion of the rod 24 which passes through an opening in the bracket. If the bracket 31 is not used, the rod 24 may be secured to the plate by heading the reduced end thereof on the outside of the annulus.

In Figure 5, there is shown a modified means for controlling the auxiliary air openings which is applicable to both of the cleaners heretofore described. Referring to this figure, the reference character 60 designates a plate which may be plain, like plate 18, or provided with vanes, like plate 47, and which is provided with sectoral openings 61 arranged about a central annulus 62 and separated by spokes 63 integral with the annulus and the outer portion of the plate, just as in Figures 2 and 4. The openings 61 are normally closed by a valve disk 64, similar to 22. A rod 65 which extends through the central opening in the annulus 62 has shoulders 66 and 67 and reduced portions 68 and 69 at its inner and outer ends, respectively. The reduced portions 68 and 69 extend through central openings in the disk 64 and the washer 70, respectively, and are headed as at 71 and 72 firmly securing the disk and the washer to opposite ends of the rod. A coiled spring 73 surrounds the pin 65, bearing at its opposite ends against the annulus and the washer, and normally holds the disk closely against the plate. A sleeve 74 having slots in its inner end in which fit the spokes 63 is secured to the plate 60 by crimping the portions of the sleeve between the slots around the inner side of the annulus, as indicated at 75. The sleeve, it will be noted, acts, through the medium of the washer, as a guide for the pin and prevents too much lateral movement of the spring.

In the operation of the air cleaner shown in Figures 1 and 2, the pipe 13 is connected to the air intake of a carburetor or other source of suction to which it is desired to supply clean air. Air is drawn through the openings 15 into the cleaner, impinges against the blades 14 which give it a rotary motion which throws the dirt to the outside and finally out of the opening 17. The cleaned air impinges against the straightener blade 16, enters the pipe 13 and due to the straightener blade loses its rotary motion, passing out of the cleaner through the pipe 13 to the source of suction. If the suction is less than a predetermined amount, the disk 22 remains seated against the plate 18 and no air is admitted through the openings 19. However, when the suction increases beyond this predetermined amount, the disk 22 moves away from the plate against the pressure of the spring 28 and additional air is admitted to

the cleaner through the openings 19 and is drawn out of the cleaner through the pipe 13.

The air cleaner shown in Figures 3 and 4 operates in a manner similar to that described both under suction below and above the predetermined amount and it seems unnecessary to give a detailed description of its operation. It is understood, of course, that a conduit leading to the source of suction will be connected to the smaller end of the cleaner by clamping the collar 13 around it. It is obvious that the valve shown in Figure 5 may be substituted for that shown in Figures 1-4 without affecting the operation of either air cleaner.

The pressure at which air is admitted to the cleaner through the auxiliary air openings is, of course, dependent on the strength of the spring used to keep the valve disk against the plate and may be varied by changing the spring or if desired a means for regulating the tension of the spring may be provided.

It is obvious that my invention is not limited to use on the types of air cleaners on which it is shown nor are the air cleaners on which it is used limited to use on induction systems of internal combustion engines.

I claim:

1. In an air cleaner, a member having an air intake opening therein, a rod secured to said member and extending therethrough, a disk slidable on the rod to control the opening, means to normally hold said disk against said member to close the opening, and a bracket for supporting the air cleaner secured to the rod.

2. In an air cleaner, a shell substantially circular in cross section, a plate closing one end of said shell and having therein a central air discharge opening and air intake openings between the central opening and the outer edge thereof and vanes adjacent said latter openings to give the air entering therethrough a rotary motion, a plate closing the other end of the shell and having openings therein arranged about a portion of said plate, and a valve to control the last named openings.

3. In an air cleaner, a body portion including a wall having therein an air discharge opening, air intake openings around the discharge opening, and vanes adjacent the air intake openings, and a second wall having therethrough a valve-controlled auxiliary air intake opening.

4. In an air cleaner, a body portion in which there is provided a main air intake opening, a main air discharge opening and an auxiliary air intake opening, vanes adjacent the main air intake opening to impart a whirling motion to the air which enters the interior of the body portion therethrough, and a valve for controlling the admission of air into the interior of the body portion through the auxiliary air intake opening.

5. In an air cleaner, a plate having openings therein arranged about a portion of the plate, openings between the first openings and the outer edge of the plate, and vanes adjacent said second openings, and a valve for controlling the first openings.

6. In an air cleaner, a shell substantially circular in cross section, means closing one end of the shell and having therein an air discharge opening, a plate closing the other end of the shell and having therein openings arranged about a portion of the plate and openings between the second openings and the outer edge of the plate and vanes adjacent the third openings to give the air passing therethrough a rotary motion, and a valve to control the second openings.

7. In an air cleaner, a body portion including a wall having therethrough an opening, openings in the wall around the first-mentioned opening, vanes adjacent said second-mentioned openings, and a valve for controlling the first-mentioned opening.

In testimony whereof I affix my signature.

MARK L. BLAIR.
